UNITED STATES PATENT OFFICE.

EDWARD PETER JOHNSON, OF GRAND FORKS, NORTH DAKOTA.

COMBINATION RULE AND BEVEL.

No. 840,628.

Specification of Letters Patent.

Patented Jan. 8, 1907.

Application filed July 12, 1906. Serial No. 325,970.

To all whom it may concern:

Be it known that I, EDWARD PETER JOHNSON, a citizen of the United States, residing at Grand Forks, in the county of Grand Forks 5 and State of North Dakota, have invented a new and useful Combination Rule and Bevel, of which the following is a specification.

This invention relates to improvements in combined rules and bevels, and has for its 10 object to improve the construction and increase the efficiency of devices of this character.

With these and other objects in view, which will appear as the nature of the invention 15 is better understood, the invention consists in certain novel features of construction, as hereinafter fully described and claimed.

In the accompanying drawings, forming a part of this specification, and in which corresponding parts are denoted by like designating characters, is illustrated the preferred 20 form of the embodiment of the invention capable of carrying the same into practical operation, it being understood that various 25 changes in the form, proportion, and minor details of construction may be resorted to without departing from the principle or sacrificing any of the advantages of this invention within the scope of the appended claims.

30 In the drawings, Figure 1 is a perspective view of the improved implement in folded position. Fig. 2 is a plan view of the improved implement in open position. Fig. 3 is a perspective view of the graduated member of the rule-joint. Fig. 4 is a perspective view of the slotted member of the rule-joint. Fig. 5 is a perspective view of the pin-carrying member of the rule-joint, Fig. 5 being in 35 reversed position to Fig. 3. Fig. 6 is a perspective view, enlarged, of the clamp-nut. Fig. 7 is a sectional view illustrating the manner in which the clamp-nut and pin are concealed and protected when the rule-sections are folded.

40 The improved device is preferably applied to the ordinary folding measuring-rule employed by carpenters and like mechanics and embraces a construction which when in folded position presents a symmetrical outline 45 without projecting parts.

In the drawings the improved device is shown applied to a carpenter's folding rule of the ordinary construction, the two blades being represented, respectively, at 10 and 11

and jointed intermediately; as at 12 13. The 55 blade 10 is also provided with spaced joint-plates 14 15 and the blade 11 provided with the intermediate joint-plate 16 of the usual "rule-joint" construction and pivotally united, as at 17. The rule-plate 15 is provided with a pin 18, threaded at the outer end and extending through an aperture 19 in the plate 14, while the plate 16 is provided with a slot 20, concentric to the pivot 17 and through which the pin 18 also extends. A 60 clamp-nut 21 engages the pin 18 exteriorly of the plate 14 and bears upon the same. By this simple means it is obvious that when the nut 21 is loosened the blades 10 11 may be opened to any required extent and clamped 65 in any desired relative position by merely operating the clamp-nut, and thus compressing the three plates 14, 15, and 16 together.

The plate 14 is provided with graduations 70 at 22, representing the degrees of a circle, and the plate 16 is provided with an index or pointer 23 to enable the blade 11 to be set at any desired degree or angle. Thus by the coaction of the graduations on the blade 14, the index on the blade 16, and the clamp-nut 75 21 the blade 11 may be adjusted to any desired angle relative to the blade 10 and firmly clamped in the adjusted position.

The blade 10 is provided with plates 24 25, conforming in outline to the combined sections 10 and 11 when folded and serving the two-fold purpose of a "housing" to the sections when in folded position and as an extension of the blade 10 for coaction with the blade 11 when the latter is adjusted at an angle thereto, as will be obvious.

Slidably disposed in the free end of the blade is a graduated bar-gage 26, having an enlarged head 27, corresponding to the curved portions of the plates 14, 15, and 16, 95 and provided with a cavity 28 to receive the nut 21 and the protruding portion of the pin 18 when the implement is in folded position, as in Fig. 1, and thus entirely concealing and protecting the nut.

The enlarged head 27 of the bar-gage conforming to the outer portions of plates 14 15 16 when the implement is in folded position, the rule-joint end of the implement presents a uniform and symmetrical appearance 105 and without protruding portions to catch upon the clothing or to be engaged by surrounding objects.

The device is simple in construction, can be inexpensively manufactured, and applied to any size or form of rule manufactured.

Having thus described the invention, what is claimed is—

1. A rule comprising jointed sections, one of said sections having a threaded pin extending therefrom and the other section having a slot to receive said pin, a clamping-nut engaging said pin, a bar-gage slidably engaging one of said sections and provided with an enlarged head having a recess formed therein for the reception of the nut and the protruding portion of said pin, and a sectional plate secured to one of the rule-sections and forming a housing for both sides of the rule when the latter is folded.
2. A rule comprising intermediately-jointed sections, a joint uniting said sections and formed of superimposed plates semicircular at the outer portions and pivotally united, housing-plates connected respectively to the jointed members of one of said rule-sections, one of said housing-plates having a semicircular terminal conforming to said superimposed joint-plates, and a bar-gage slidably engaging one of said rule-sections and provided with an enlarged head conforming to the superimposed plates and bearing upon the same when the implement is in folded position.
3. A rule comprising laterally-movable sections, a joint uniting said sections and formed of superimposed plates pivotally united, means for clamping the sections in

adjusted position, a bar-gage slidably engaging one of said sections and having an enlarged head corresponding to said joint-plates and bearing upon the same when the sections are in folded position, said head being provided with a recess for the reception of the clamping means, and a sectional plate secured to one of the rule-sections and forming a housing for both sides of the rule when the latter is folded.

4. A rule comprising two sections, a joint uniting said sections and formed of superimposed plates pivotally united, a bar-gage slidably engaging one of said sections and having an enlarged head corresponding to said joint-plates and a sectional plate secured to one of the rule-sections and forming a housing for both sides of the rule when the latter is folded.

5. A rule comprising pivotally-united sections, clamping means piercing the pivoted ends of said sections, a bar-gage slidably engaging one of said sections and having an enlarged head provided with a recess for the reception of the clamping means, and a sectional plate secured to one of the rule-sections and forming a housing for both sides of the rule when the latter is folded.

In testimony that I claim the foregoing as my own I have hereto affixed my signature in the presence of two witnesses.

EDWARD PETER JOHNSON.
